UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 15,175, dated July 29, 1884.

Application filed May 13, 1884. Term of patent 34 years.

To all whom it may concern:

Be it known that I, DAVID G. MELVILLE, of Medford, in the county of Middlesex and State of Massachusetts, have invented a new and original Design for Carpets, of which the following is a specification.

The nature of my design is fully shown in the accompanying photographic illustration.

The design is composed of the masses of flowers and foliage and the surrounding floral and foliage ornamentation, arranged on the ground of the carpet, as shown.

I claim—

The design for a carpet, substantially as shown and described.

In testimony whereof I have signed my name to this specification, in the presence of two subscribing witnesses, this 5th day of May, 1884.

DAVID G. MELVILLE.
